(57) **CLAIM**

The ornamental design for a container dispenser, as shown and described.

DESCRIPTION

FIG. 1 is a front elevation view of the container dispenser (shown with a container in broken lines) according to the new design;

FIG. 2 is a back elevation view thereof;

FIG. 3 is a left side elevation view thereof;

FIG. 4 is a right side elevation view thereof;

FIG. 5 is a perspective view thereof;

FIG. 6 is a top plan view thereof; and,

FIG. 7 is a bottom plan view thereof.

The broken lines in the Figures serve the purpose of illustrative example and form no part of the claimed design.
